UNITED STATES PATENT OFFICE.

JOHN A. MATHES, OF SAN DIEGO, CALIFORNIA.

KEROSENE-VAPOR STOVE.

No. 823,784.

Specification of Letters Patent.

Patented June 19, 1906.

Application filed December 13, 1904. Serial No. 236,653.

To all whom it may concern:

Be it known that I, JOHN A. MATHES, a citizen of the United States, residing at San Diego, in the county of San Diego, State of California, have invented certain new and useful Improvements in Kerosene - Vapor Stoves, of which the following is a specification.

This invention relates to burners for utilizing kerosene as a fuel for cooking and heating purposes and the like, and has for its primary object the provision of extremely simple, compact, and durable means for vaporizing kerosene and burning the vapor intermingled with air for generating heat either for cooking, heating, or other purposes.

A further object of the invention is to provide a combined vaporizing and air-mixing apparatus in which the vaporizing-chamber shall be so located with relation to the air and vapor mixing chamber and with relation to the flame that the mixing-chamber shall be in the heat zone of the main flame from the burner, and the vaporizing-chamber shall be heated from a portion of the same flame which is utilized for heating or cooking, the relations and positions of the vaporizing-chamber and the mixing-chamber being such that all portions of the mixing-chamber as well as all portions of the vaporizing-chamber are in heat-receiving relation to the burning flame, so that the vapor generated by the vaporizing-chamber and passing in the air-mixing chamber is not brought in contact with any cold or cool surface, so that condensation of the vapor can take place, but is at all times maintained subject to sufficient heat to prevent condensation without subjecting the vapor in the mixing-chamber to too great a degree of heat.

A further object of the invention is to provide such generating and air-mixing apparatus in such form and so arranged that the vaporizing-chamber while receiving sufficient heat from the burning flame of the burner to generate a dry gas or vapor, yet the heat will not be so great as to prevent the proper mixture of the air and vapor in the mixing-chamber.

A further object of the invention is to provide the vaporizing-chamber at one side of the mixing chamber, so that the initial heating of the vaporizing-chamber by alcohol flame or any other means can be readily attained without interfering in any manner with the vaporizing-chamber or other part or

parts of the burner and the provision in connection with such vaporizing-chamber so lying at the side of the mixing-chamber of a portion of the burner proper extending downward at the side of the vaporizing-chamber and in open connection with the main portion of the burner, so that it is impossible for the flame which heats the vaporizing-chamber to be extinguished while the main burner is in operation, or vice versa, and, further, for the provision of a covering or hood over the vaporizing-chamber, so that in the initial heating of the vaporizing-chamber all heat from the alcohol flame or other means can be localized upon the generator to readily heat the same and to retain the heat from the vaporizing portion of the flame upon the vaporizing-chamber when the burner is in operation.

The invention will be more readily understood by reference to the accompanying drawings, forming a part of the specification, and in which—

Figure 1 is a plan view of the burner embodying my invention. Fig. 2 is a longitudinal sectional view on the line X² X² of Fig. 1. Fig. 3 is a longitudinal sectional view on the line X³ X³ of Fig. 1. Fig. 4 is a partial plan view with the slotted burner-top removed and showing the mixing-tube, vaporizing-chamber, and valve in section. Fig. 5 is a side view with the valve and hood removed, showing the relation of the vaporizing-chamber to the burner-flame.

As shown in the drawings, 2 represents a cylindrical casing, within which is formed the mixing-chamber 3. This casing 2 has a closed bottom 4 and an open top 5. Upon the top of the casing 2 the slotted burner-top 5 rests of its own weight. If desired, this slotted burner-top 5 may be formed integral with the cylinder 2 or otherwise firmly attached thereto. The slotted burner-top 5 is in a single piece of metal having parallel longitudinal vapor-slots 6. Formed integral with the cylindrical casing 2 and extending downward at one side thereof is an air-draft tube 7, having an open bottom and a closed top.

8 represents a mixing-tube extending through the wall of the casing 2 and opening into the chamber 3, whereby communication is had from the chamber 9 of the air-tube 7 into the chamber 3. This tube preferably extends nearly across the chamber 3, so that the air and vapor from the tube 8 is projected

against the cylindrical wall of the casing 2, deflecting the same around the wall thereof and creating an intense commotion with the vapor and air within the mixing-chamber 3, insuring the perfect admixture of the air with the vapor.

At one side of the air-tube 7 the wall of the casing 2 is provided with downwardly-projected parallel slots 10, forming a slotted burner 11, which, in effect, is a continuation of the slotted burner 5. This slotted burner 11 may, if desired, be formed as a part of the burner 5 and a portion of the wall of the casing 2 cut away to receive the same. Preferably the burner portion 11 is arched, so as to provide for greater area in the inlet-chamber 9. The bottom or edge of this part 11 when so arched preferably rests on the casing 2, the vertical sides of the flange 12 forming closures, so that the chamber 3 is closed at the ends of the part 11. Positioned in place alongside the burner part 11 is a pipe or tube 13, which forms the generating-chamber or vaporizer. This vaporizer has a small vapor-outlet 14, opening through the air-tube 7 in line with the mixing-tube 8. As the burner 11 is extended down one side of the casing 2 and the vaporizing-tube or vaporizer 13 is arranged sidewise and transversely to this side burner or generating-burner 11 I am able to accomplish two important results. First, I am able to construct my burner with great compactness; second, to bring all portions of the outer surface of the vaporizer 13 between the inlet and outlet of the vaporizer into direct contact with the flame of said slotted side of the casing. This is of extreme importance in the vaporization of kerosene, and it is equally of importance that the inlet end of the vaporizing-tube should not be directly in the heating-flame, as it is advantageous not to project the oil flowing in the vaporizing-tube into too great a heat at the point of its introduction into the tube. 15 represents the oil-supply pipe, which is connected with any suitable source of supply, preferably under gravity-pressure. This oil-supply pipe 15 is connected with the vaporizing-tube by a smaller portion or section 16. The object of making this section 16 smaller in diameter than the supply-pipe 15 is to prevent the supply of oil in pipe 15 and the metal of the tube from drawing the heat from the tube 13. 15 Preferably the tube 13 is inclined with respect to the horizontal, so that the inlet end is lower than the outlet. By thus inclining the vaporizing-tube 13 the natural tendency of the oil as it is heated to rise is taken advantage of, and the vaporizing-oil rising toward the upper end of the vaporizing-tube 13 is converted into vapor before it reaches the outlet 14. By thus arranging the outlet 14 above the inlet into the vaporizing-tube 65 the absolute vaporization of the oil is insured

and all possibility of non-vaporized oil flowing to the outlet obviated. By thus preventing the non-volatilized oil from approaching the outlet end I am also able to provide the greatest heat in the outlet end of the tube 13, thus insuring the most complete volatilization. This is of great importance with kerosene, as the same condenses rapidly.

17 represents a valve-casing, preferably of sufficient length to carry the packing-box 75 away from the heat zone, so that the heat from the burner will not deteriorate the packing, causing the valve to leak. Inside of this casing 17 is a valve-stem 19, which fits snugly within the casing 17 and has at its 80 inner end a cylindrical pin-valve 18 adapted to operate in the vapor-outlet 14 of the vaporizing-tube 13. The stem 19 passes through a suitable packing within a packing-box 20 and is provided with a packing-nut 21. The 85 stem 19 is provided with an enlarged screw-threaded end 22, engaging a thread in the flange 23, thus providing the threaded parts of large diameter outside of the packing-box and packing-nut. The stem 19 is provided 90 with a suitable operating-head 24 of the ordinary or any preferred style or construction.

Inside the casing 2 and near the portion of the wall thereof which the air-tube 8 terminates I provide a low wall 25, forming a separate cup 26. This wall 25 is preferably extended up so that it is slightly above the level of the bottom of the chamber of the tube 8. The cup 26 thus formed is entirely cut off by the wall 25 from communication with the other portion of the chamber 3, except over the wall 25. It is thus seen that in case the generator should cool from any cause—such, for instance, as a sudden gust of wind blowing out the flame from the burner or from water boiling over when the burner is in operation—the oil forced through the tube 13 into the tube 8 will fill the cup 26; but as the wall 25 is slightly higher than the bottom of the tube 8 the oil will then run 100 back out of the tube 8 and down the air-chamber 9 into any suitable receptacle or onto a stove-pan, as means are provided therefor, thus preventing the flooding of the entire chamber 3 and causing the production 105 of a large amount of partially-burned and evil-smelling vapor.

Preferably formed integral with the flange 5' of the burner-top 5 is a hood 27, which, as shown, is extended out over the generating 110 or vaporizing tube 13 and downward opposite the part 11 of the burner. This hood 27 is preferably provided in its top with an opening 28 directly above the vertical slots of the part 11, so that the flame from the upper portion of the burner and the flame from the side portion 11 of the burner are in communication, and each insures the continuous burning of the vapor issuing through the other.

29 represents a light filling within the vap-

orizing-tube 13, being shown in the drawings as a series of twisted fine wires. If preferred, gauze might be used in place of the wires. The object of this filling 29 is to prevent puffing of the burner due to irregularity of the vaporization within the tube 13. The use of a light filling within the tube 13 distributes the heat evenly throughout the vaporizing-chamber, causing equal vaporization and also constant vaporization. The use of such filling also prevents the deposit of carbon, as such light filling is more readily heated to the same degree as is the wall of the tube 13.

15 By extending the part 11 of the burner and generating-tube 13 at an acute angle to the tube 8 I am able to bring the vaporizing or generating tube 13 in closer proximity to the burner and secure great compactness.

20 It is preferable in constructing this burner to provide the tube 8 of such diameter as to provide an excess of air in the mixing-chamber 3, so that the vapor from the vaporizing-tube 13 is mixed in the chamber 3 not only with just sufficient air to burn on the burner 5 with a blue flame, but with a sufficient amount of air so that the flame will be of a more intense temperature, thus effectually providing against any condensation by reason of the 25 thorough heating of the generating-tube 13 and casing 2, and the supply of such excess of air most thoroughly commingled with the vapor.

30 It is thus seen that with this construction and arrangement all parts of the burner are in intimate relation with the heat zone and that no part of the mixing-chamber is away from the heat zone, so as to present any unheated surface to the vapor which would 35 cause condensation thereof.

40 Preferably the top 5 of the burner is slightly depressed below the flange 5'. One of the advantages thus secured is that the flange 5' prevents air from the outside of the burner 45 mixing with the vapor as it rises from the mixing-chamber 3. This is found to be of advantage when the burner is first lighted, and when the burner is being extinguished all of the vapor rising therefrom being thoroughly 50 consumed and no fumes are precipitated in the room when the burner goes out.

55 By arranging the generating-tube at the side of the casing 2 much more ready access can be had to the tube 13 for starting the burner in operation. It will also be noted that with this burner the side portion of the flame heats the generator not only at its central portion, but also at its upper and discharge end.

60 30 represents a clean-out plug at the lower end of the tube 13, by means of which access may be had to the vaporizing-chamber through which the light filling 29 may be removed and replaced, as desired. It will be noted that this clean-out plug as well as the

oil-supply pipes 15 16 are outside the heating flame.

The vaporizing-tube 13 provides a single straight unitary vaporizing-chamber where-in equal vaporization of all of the kerosene is insured, and by the provision of the clean-out plug 30 this single straight unitary vaporizing-chamber may be most readily cleaned of all deposits of carbon and impurities carried by the oil. It has been found in the use of 75 kerosene-vapor stoves that it is highly important to provide against such deposits in the vaporizing-chamber, and to accomplish this desired result in the most simple manner I have provided a single straight vaporizing-tube having a single unitary and straight vaporizing-chamber, the vaporizing-tube being arranged alongside of and transversely to the downwardly-extending slotted portion of the burner, so that I am able to combine the 80 advantages of such a single straight unitary vaporizing-chamber and a unitary flame at the main burner and the vaporizing-burner and completely surround the walls of the vaporizing-chamber with the flame. By arranging such vaporizing-tube transversely to or across the downwardly-extending side burner and at the side thereof the flame comes in intimate contact with all portions of the tube and particularly with the lower portion of the periphery thereof. A marked advantage is secured by so arranging the vaporizing-tube, as if the same is arranged substantially vertical the flame is not retained 85 against the walls of the tube and the vaporizing-chamber is not effectually heated. Furthermore, by the construction shown the vaporization of the oil does not depend upon the conduction of heat from one portion of the vaporizer in direct contact with the flame to 90 other portions which are not in direct contact therewith, and I am also enabled to provide the greatest heat at the outlet end of the vaporizing-chamber.

95 Having thus described my invention, I claim as new and desire to secure by Letters Patent—

1. A burner, comprising a cylindrical casing having an open top, a burner-plate arranged on said top, and a slotted side portion forming a downwardly-extending continuation of said burner-top, a mixing-chamber, a single straight vaporizing-tube having a single vaporizing-chamber arranged alongside of and transversely to said downwardly-extending slotted side portion and positioned to be in direct contact with the flame therefrom, an air-mixing tube extending from proximity to said vaporizing-tube into said mixing-chamber, avelved outlet from said vaporizing-chamber into said air-mixing tube, and means for supplying oil to said vaporizing-tube.

2. A burner comprising a casing having a mixing-chamber and provided with a slotted

- burner extending over the top of said chamber and down one side of said casing, a single straight vaporizing-tube having a unitary vaporizing-chamber arranged alongside of and transversely to said downwardly-extending slotted side of said casing, said tube having all portions of its outer surface between the inlet and outlet thereof in direct contact with the flame from said slotted side of said casing, a mixing-tube extending from proximity to said vaporizing-tube into said mixing-chamber, an outlet from said vaporizing-tube opening into said mixing-chamber, and means for supplying oil to said vaporizing-tube.
3. A burner comprising a hollow body having an imperforate bottom, a perforate top, and a cylindrical wall, only a portion of which is perforate, said perforated portion forming a downward side extension of said perforate top of said body, thus forming a unitary mixing-chamber, all portions of which intercommunicate, a single straight vaporizing-tube arranged alongside of and transversely of said perforated side and in direct heat-receiving relation thereto, said vaporizing-tube communicating into said mixing-chamber through an inlet thereinto of larger diameter than the diameter of the outlet from said vaporizing-tube, and means for supplying oil to said vaporizing-tube.
4. A burner comprising a short hollow cylindrical body having an imperforate bottom, a perforate top, a cylindrical wall forming a unitary mixing-chamber, all portions of which directly intercommunicate, a portion of said wall being downwardly perforated and forming a downward side extension of said perforate top, a vaporizing-tube arranged sidewise to and transversely of said downwardly-extending perforate side and in direct heat-receiving relation thereto, the inlet and outlet of said vaporizing-tube arranged just beyond the limit of perforation of said side and having all its intermediate portions between said inlet and outlet in direct contact with the flame from said perforate side extension, an air-mixing tube extending into said chamber, an air-tube extending from below said body and opening into said mixing-tube, said vaporizing-tube provided with a peripheral outlet arranged opposite and opening into the inlet end of said mixing-tube, a valve arranged transversely of said vaporizing-tube to control said outlet, a light filling in said vaporizing-tube and means connected with the inlet end of said vaporizing-tube for supplying oil to said vaporizing-tube, said vaporizing-tube having its outlet above its inlet.
5. A burner comprising a body having a mixing-chamber, a single straight vaporizing-tube having a single unitary vaporizing-chamber arranged alongside of and transversely of the side of said body, said body provided with a slotted top and with a slotted side opposite said vaporizing-tube, a hood over and embracing said vaporizing-tube, said hood provided with an opening permitting the union of the flame between said slotted top and slotted side, a mixing-tube in said chamber, an air-tube extending from below said body into communication with said mixing-tube, said vaporizing-tube provided with a peripheral outlet opening opposite the inlet end of said mixing-tube, a valve extending transversely through said vaporizing-tube to control said outlet, said vaporizing-tube having all portions of its outer surface between the inlet and outlet in the flame of said slotted side and means for supplying oil to said vaporizing-tube, said vaporizing-tube having its outlet above its inlet.
6. A burner comprising a body having a mixing-chamber all portions of which directly intercommunicate, said body having a slotted top and a downwardly-extending slotted side, a single straight vaporizing-tube having a single unitary vaporizing-chamber arranged alongside of and transversely of said slotted side, a mixing-tube extending into said mixing-chamber, said vaporizing-tube provided with a peripheral outlet opening into the inlet end of said mixing-tube, means for supplying oil to said vaporizing-tube at a point below said outlet, and a hood over and enveloping said vaporizing-tube, said hood provided for intercommunication between the flame from said slotted top and said slotted side.
7. A burner comprising a short hollow cylindrical body having an imperforate bottom, a perforate top and a cylindrical wall forming a unitary mixing-chamber, all portions of which directly intercommunicate, a portion of said wall being downwardly perforate, and forming a downward side extension of said perforate top, a vaporizing-tube having a single unitary vaporizing-chamber arranged sidewise to and transversely of said downwardly-extending perforate side and in direct heat-receiving relation thereto, a light filling loose in said vaporizing-tube, means for supplying oil to said vaporizing-tube, said vaporizing-tube having a peripheral outlet into said mixing-chamber, and an inlet below said outlet, and means for admitting air to said mixing-chamber.
8. A vapor-burner comprising a short hollow body having an imperforate bottom, a perforate top and a cylindrical wall forming a unitary mixing-chamber, all portions of which directly intercommunicate, a portion of said wall being downwardly perforated and forming a downward side extension of said perforate top, a single straight vaporizing-tube having a single vaporizing-chamber arranged sidewise to and transversely of said downwardly-extending perforated side and in direct contact with the flame therefrom,

means for supplying oil to said vaporizing-tube, said vaporizing-tube having a peripheral outlet into said mixing-chamber, and an inlet at its other end and below the level of 5 said outlet, a valve for said peripheral outlet, the stem of said valve extending transversely through said vaporizing-tube and means for admitting air to said mixing-chamber.

9. A burner comprising a body having a 10 mixing-chamber, said body provided with a slotted top and a downwardly-extending slotted side, a single straight vaporizing-tube having a single unitary vaporizing-chamber arranged at the side of and transversely of said 15 slotted side, said vaporizing-tube having all portions of its outer surface, between the inlet and outlet thereof, in direct contact with the flame from said slotted side, a light filling in said vaporizing-tube, an air-mixing tube 20 in said mixing-chamber, said vaporizing-tube provided with a peripheral outlet opening into said air-mixing tube, a valve for said peripheral outlet, a valve-stem for said valve extending transversely through said vaporizing-tube and means for supplying oil to said 25 vaporizing-tube.

10. A burner comprising a body having a mixing-chamber all portions of which directly intercommunicate, said body having a slotted top and a downwardly-extending slotted side, a single vaporizing-tube having a single unitary vaporizing-chamber arranged alongside of and transversely of said slotted side, and having a peripheral outlet, a mixing-tube extending into said mixing-chamber 30 into which said peripheral outlet communicates, a valve for said peripheral outlet, a valve-stem for said valve extending transversely through said vaporizing-tube, means for supplying oil to said vaporizing-tube and 35 a hood over and enveloping said vaporizing-tube, said hood provided with a perforation allowing the union of the flame of said slotted top and slotted side.

In testimony whereof I have hereunto set 45 my hand, at Los Angeles, California, this 6th day of December, 1904.

JOHN A. MATHEIS.

In presence of—

FREDERICK S. LYON,
TILLIE E. ADAM.
